SINGLE-LINE HYDRAULIC SYSTEM

Nasser D. Owen, Albuquerque, N. Mex.

Application May 27, 1944, Serial No. 537,665

4 Claims. (Cl. 60—52)

Granted under the act of March 3, 1883, as
amended April 30, 1928; 370 O. G. 757

The invention described herein may be manufactured and used by or for the Government for governmental purposes, without the payment to me of any royalty thereon.

This invention relates to hydraulic systems and more particularly to apparatus for controlling a hydraulic servomotor at a point remote from the operator through a single pipe.

An object of the invention is to generally simplify devices of this character.

More specifically, an object of the invention is to eliminate a considerable portion of the piping usually required in systems of this kind.

Another object is to simplify the valving in a device of this general character.

Other objects and advantages will appear as the invention is further described and reference is had to the drawing, wherein:

Fig. 1 is a schematic view of an embodiment of my invention in its simplest form.

Fig. 2 is another schematic view of the invention showing a modification of certain parts.

Fig. 3 is another schematic view showing a modification of the pumping means of the system.

Similar reference characters refer to similar parts throughout the several figures of the drawing.

Referring more particularly to Fig. 1, a hydraulic servomotor 10 comprises a cylinder 12 in which a piston 14 is axially slidable. Piston 14 is mounted on a piston rod 16, the piston being secured against axial movement, with respect to the rod, by nuts 18. Stops 20 and 22 are provided to limit the axial movement of the piston in the cylinder. The ends 24, 26 of the piston rod 16 are suitably formed for connecting to the various devices which are to be operated.

The ends of the cylinder 12 are closed by heads 28 and 30 which also provide bearings for the piston rod 16. The piston 14 divides the enclosed space within the cylinder 12 into compartments 29 and 31. Passageways 32 and 34 extend through the cylinder walls from the compartments 29 and 31 into chambers 36 and 38, respectively, these chambers being closed on the underside by the flexible diaphragms 40 and 42, respectively. Caps 44 and 46 clamp the diaphragms in place, thus making the chambers 36 and 38 pressure tight.

The spaces 48 and 50 within the caps 44 and 46 are, however, connected to the atmosphere by any suitable openings as at 52 and 54. Springs 56 and 58 urge the diaphragms 40 and 42 downward, whereas the negative pressure caused by movement of the piston 14 to enlarge the compartments 29 or 31, urges them upward. Since 55

chambers 36 and 38, in the normal condition, are resiliently held to their maximum volume but may be contracted by negative pressure in the compartments 29 or 31, chambers 36 or 38 may be referred to as contraction chambers. Buffer springs 60 and 62 arrest further downward movement of the diaphragms when the positive pressure in chambers 36 or 38 becomes too great.

A pulsating pump 64 comprises a pump cylinder 66 having a reciprocating piston 68 slidably therein, and a connecting rod 70 hinged to a pump handle 72 at 74, the pump handle being hinged at 76 to a bracket 78 extending from the cylinder 66.

The rotatable valve mechanism 80 has a valve body 82 which may be cast integral with the cylinder 12 or made separately as desired. A cylindrical valve plug 84 is snugly fitted to the body 82 but may be rotated through one quarter turn by means of the lever 86 which may be operated from a remote position by any suitable means such as the rod 88.

The inside of the valve plug 84 is chambered out as at 90, and fluid from the pump 64 is carried through a main supply pipe 92 which connects with this chamber from the rear through an opening 94 which is concentric with the plug. Diametrically opposite valve openings 96 and 98 and another valve opening 100 spaced ninety degrees from the other two, extend from the perimeter of the plug 84 radially inward into the chamber 90.

Spring loaded check valves 102 and 104 are biased to prevent fluid flow outward through the openings 96 and 98, respectively, and another spring loaded valve 106 is biased to prevent fluid flow inward through the opening 100. Fluid passages 107 and 108 are provided for connecting the chambers 36 and 38 to the several valve openings 96, 98, or 100. Since the setting of the valve mechanism 80 determines the direction which the servo piston 14 will move, the valve mechanism 80 may preferably be called the selector valve, and since the check valve 106 allows fluid flow into the servomotor, it may be called the inflow check valve, while the check valves 102 and 104, being biased for flow out of the servomotor, may be termed outflow check valves.

The system should be completely filled with hydraulic fluid with the pump piston 68 and the diaphragms 40 and 42 in the respective positions shown in Fig. 1 of the drawing. The operations of the device of Fig. 1 may preferably be carried out substantially as follows:

Let it be assumed, for example, that it is de-

sired to move the servo piston 14 to the right. The operator first positions the lever 86 of the selector valve as shown in Fig. 1 of the drawing. If the pump piston 68 is now moved left, fluid will be drawn from the contraction chamber 38, through the outflow check valve 104 to the pump. The large piston 14, however, can not at this time move right to replace the fluid drawn from the contraction chamber 38 because, while the pump 64 is drawing fluid from the contraction chamber 38, it is also drawing the inflow check valve 106 shut, whereby no fluid may enter the contraction chamber 36, and therefore, since the servo piston 14 may not move right, the diaphragm 42 rises to an upper position 109 by compressing the spring 58.

When, however, the direction of the pump piston 68 is reversed, i. e., moved to the right to the position shown, fluid will be forced from the pump through the inflow check valve 106 into the contraction chamber 36 and through the opening 32 into the compartment 29 of the cylinder 12, whereupon the servo piston 14 moves right and the diaphragm 42 is brought back by the spring 58 from its upper position 109 to the normal position shown.

This completes one pump cycle. The distance which the servo piston 14 moves right per pump cycle depends, of course, on the relative displacements of the pump piston 68 and the servomotor piston 14.

Movement of the lever 86 of the selector valve clockwise through one quarter turn conditions the device of Fig. 1 for movement of the servo piston 14 to the left, since it provides the contraction chamber 36 with chamber-to-pump valving, and the contraction chamber 38 with pump-to-chamber valving which is the opposite of that shown in Fig. 1 of the drawing, whereby each pump cycle moves the servo piston 14 to the left an amount equal to that which it before moved to the right, in which case the chamber 36 instead of the chamber 38 will be contracted.

In the modification shown in Fig. 2, the servomotor 110 has a cylinder 112 with an elongated hollow piston 114 slidable axially therein, and a piston rod 116 extending axially from the piston. A disc 118 is secured in the interior of the piston about midway of its length. Stops 120 and 122 are provided to limit axial movement of the piston in the cylinder. The piston rod 116 has a longitudinal opening 124 extending therethrough and the end is appropriately formed as at 126 for connection to the device which is to be operated.

Heads 128 and 130 close the ends of the cylinder 112, the hollow piston rod 116 having sliding bearing in the head 130. The piston 114 divides the space enclosed within the cylinder 112 into two main compartments 129 and 131. Passageways 132 and 134 extend through end enclosing portions 133 and 135 of the hollow piston 114 to connect the chambers 136 and 138 with the main compartments 129 and 131, the inner end walls of the compartments 129 and 131 being formed by the short pistons 140 and 142, respectively, which are slidably fitted to the interior of the elongated hollow piston 114. The spaces 148 and 150 between the pistons 140 and 142 are connected together by the openings 144, and to the atmosphere by a series of connected passageways 146, 152, 124, and the transverse opening 154.

Springs 156 and 158 urge the pistons 140 and 142 toward each other, whereas the negative pressure caused by movement of the piston 114 away

from the heads 128 or 130 to thereby decrease the volume of the compartments 129 or 131 urges them to move farther apart. Since the chambers 136 and 138 are contracted by the presence of sub-atmospheric pressure in the compartments 129 or 131, the chambers 136 and 138 may preferably be referred to as contraction chambers. Buffer springs 160 and 162 retard further movement of the pistons 140 and 142 toward each other when the positive pressure in contraction chambers 136 or 138 becomes too great.

A pulsating pump 64 which is an exact duplicate of that shown in Fig. 1 is employed in the modification shown in Fig. 2.

15 The rotatable valve mechanism 180 has a valve body 182 which may be an integral part of the cylinder 112 as seen in Fig. 1 or may be separated as shown. The rotatable valve 180 except for the difference in the body 182 is a duplicate of the rotatable valve 80 of Fig. 1. Fluid conduits 207 and 208 are provided for connecting the contraction chambers 136 and 138 to the several valve openings 96, 98, or 100. Since the setting of the valve mechanism 180 determines the direction which 20 the servo piston 114 will move, the valve mechanism 180 may preferably be called the selector valve, and since the check valve 106 allows fluid flow into the servomotor, it may be called the inflow check valve, while the check valves 102 and 104, being biased for flow out of the servomotor, 25 may be termed outflow check valves.

The system should be completely filled with hydraulic fluid with the pump piston 68 and the narrow pistons 140 and 142 in the respective positions shown in the drawing.

35 The operation of the embodiment of Fig. 2 may preferably be carried out substantially as follows:

Let it be assumed, for example, that it is desired to move the servo piston 114 to the right. The operator will first place the lever 86 of the selector valve in the position shown in the drawing. If the pump piston 68 is now moved left, fluid will be drawn from the compartment 131 and consequently from the contraction chamber 138 through the outflow check valve 104 to the pump. The elongated servo piston 114, however, can not at this time move right to replace the fluid drawn from the contraction chamber 138 for the reason that, while the pump 64 is drawing fluid from the contraction chamber 138, it is also drawing the check valve 106 shut, whereby no fluid may enter the contraction chamber 136, and therefore, since the servo piston 114 may not move right, the narrow piston 142 moves right by compressing the springs 158.

55 When, however, movement of the pump piston 68 is reversed so as to move to the right, to the position shown, fluid will be forced from the pump through the inflow check valve 106 into the compartment 129 and contraction chamber 136, 60 whereupon the servo piston 114 moves to the right, and the narrow piston 142 is moved back, by the springs 158 to its normal position shown in the drawing.

65 This completes one pump cycle, the movement of servo piston 114 per one pump cycle depending on the relative displacements of the pump piston and the servo piston.

Movement of the lever 86 of the selector valve 70 clockwise through one quarter turn conditions the device of Fig. 2 for movement of the servo piston 114 to the left, since it provides the contraction chamber 136 with chamber-to-pump valving and the chamber 138 with pump-to-chamber valving which is opposite to that shown

in Fig. 2 of the drawing, whereby each pump cycle moves the servo piston 114 to the left an amount equal to that which it before moved to the right.

From the foregoing description, it will be evident that the gist of the invention lies in providing pumping means capable of producing, in the main supply pipe, a flow of fluid alternating outward from the pump to the servomotor then back from the servomotor to the pump, with valving means which will direct the outward flow into one end of the servo cylinder and withdraw fluid for backward flow from the other end of the servo cylinder.

In the devices shown in Figs. 1 and 2 alternate flow in the main supply pipe is achieved by merely employing, as a pumping means, a piston, and a cylinder with one end closed, whereby movement of the piston toward the closed end causes outward flow of fluid in the supply pipe, and movement of the piston away from the closed end causes return flow of fluid in the supply pipe.

There are, however, situations where a pump of uniform delivery such as a sliding vane pump or a gear pump is preferably employed. In such a situation, means is necessarily provided for causing the uniform flow from the discharge side of the uniform delivery pump to flow first in one direction then in the other within the supply pipe. Such an arrangement is shown in Fig. 3 of the drawing.

Referring now to Fig. 3, a power driven gear pump 210 has its suction side 212 connected by a pipe 214 to a supply tank 216 and its discharge side 218 connected by a pipe 220 to the inlet side 222 of an automatic valve 224, the outlet side 226 of the valve 224 being connected by a pipe 228 to the main supply line 230, the function of the automatic valve 224 being to create an alternating fluid flow in the supply pipe 230.

The automatic valve 224 has a body 232 with a cylindrical bore 234 adapted to slidably receive a small piston 236. Piston 236 is resiliently held against the bottom wall of the cylindrical bore 234 by a spring 238. A piston rod 240 extends downwardly from the piston through the bottom wall of the bore 234 into a compression chamber 242. Piston rod 240 has a laterally extending bracket 244, the outer end of which supports the valve heads 246 and 248 which are on a common stem which is vertically slidable in the bracket.

Springs 250 around the stem above and below the bracket cushion the seating of the valve heads. When the upper head 246 is off its seat, the pressure chamber 242 is in communication with the valve outlet 226, and when the valve head 248 is off its seat, the pressure chamber 242 is in communication, through a short pipe 252, with the return pipe 254 which leads back to the pump inlet 212.

The piston 236 has a groove 256 around it, which, when the piston moves upward, connects the valve outlet 226 to the return pipe 254. A small spring loaded ball valve 258 allows such fluid as leaks past the upper end of the piston to return through the pipe 260 to the return pipe 254.

An emergency hand pump 262 is provided in case the power pump 210 should fail. Hand pump 262 has a cylinder 264 with piston 266 operated through a connecting rod 268 by handle 270. Hand pump 262 draws fluid by way of the pipe 272 from the same source as the power pump. Conventional valves 274 and 276 are placed in the bottom of the cylinder and in the piston respectively. A discharge pipe 278 delivers the fluid

from the hand pump to a pressure tank 280. A valve 282 may be turned by the handle 284 to connect the pressure tank 280 through the inlet 222 to the compression chamber 242.

5 The hydraulic servomotor 310, which is operated by means of the alternating flow in the supply pipe 230, comprises a cylinder 312 in which a piston 314 is axially slidable. Piston 314 is mounted on a piston rod 316, the piston being secured against axial movement on the rod by nuts 318. Stops 320 and 322 are provided to limit the axial movement of the piston in the cylinder. The end 326 of the piston rod is suitably formed for connection to the device which is to be operated.

10 The ends of the cylinder 312 are closed by heads 328 and 330, the head 330 providing bearing for the piston rod 316. The piston 314 divides the enclosed space within the cylinder 312 into compartments 329 and 331. Passageways 332 and 334 extend through the cylinder walls from the compartments 329 and 331 into chambers 336 and 338, respectively, these chambers being closed on the underside by the flexible diaphragms 340 and 342, respectively. Caps 344 and 346 clamp the diaphragms in place, thus making the chambers 336 and 338 pressure tight. The spaces 348 and 350 within the caps 344 and 346 are, however, connected to the atmosphere by any suitable 15 openings as at 352 and 354. Springs 356 and 358 normally hold the diaphragms in the upwardly deflected position shown while a positive pressure of a predetermined value in the chambers 336 or 338 forces the diaphragms to an equally deflected downward position 341 and 343. Since the chambers 336 and 338 are adapted to expand from their normal volume by superatmospheric pressure in the compartments 329 and 331, the chambers 336 and 338 may be referred to as expansion chambers.

20 The rotatable selector valve mechanism 380 has a valve body 382 which may be cast integral with the cylinder 312 or made separately if so desired. A cylindrical valve plug 384 is snugly fitted to the body 382 but may be rotated through one quarter turn by means of the lever 386 which may be remotely controlled as by a cable 388 and returned to normal position by a spring 389. A lever 391 within convenient reach of the operator is provided for drawing up the cable.

25 The inside of the valve plug 384 is chambered out as at 390, fluid from the automatic valve 224 alternately flowing to and from the chamber 390 by way of the long supply pipe 230 which connects to this chamber from the rear through an opening 394 which is concentric with the plug. Diametrically opposite valve openings 396 and 398, and another valve opening 400 spaced ninety degrees from the other two, extend from the perimeter of the plug 384 radially inward into the chamber 390.

30 Spring loaded outflow check valves 402 and 404 are biased to allow fluid flow outward through the openings 396 and 398, respectively, and another spring loaded inflow check valve 406 is biased to allow flow inward through the opening 400. Fluid passages 407 and 408 are provided for connecting the chambers 336 and 338 to the several valve openings 396, 398, and 400. The system should be completely filled with the hydraulic fluid when the diaphragms 340 and 342 are in the positions shown in Fig. 3 of the drawing. Fluid will then be added from the tank 216 if and when it is required. The operation of the device

of Fig. 3 may preferably be carried out substantially as follows:

Let it be assumed, for example, that it is desired to move the servo piston 314 to the right. The operator will first place the lever 386 of the selector valve as shown in Fig. 3 of the drawing. If the power pump 210 is now operating, fluid will flow from the pump outlet 218 into the automatic valve at 222, into the compression chamber 242 and out past the valve head 246 which is now unseated, through 226, 228 and the main supply pipe 230 in which the fluid moves to the right, entering the selector valve chamber 390 and flowing thence through the inflow check valve 406 into the expansion chamber 336.

Continuing flow into expansion chamber 336 deflects the diaphragm 340 downward to the position 341, then moves the piston 314 to the right far enough to force the diaphragm 342 down to the position 343; then the piston 314 must stop because there is no outflow through the passage 408 because the pressure in the chamber 390 is holding the outflow check valve 404 closed.

When the servo piston 314 stops moving to the right, the pressure builds up in the compression chamber 242 of the automatic valve, causing the piston rod 240 to rise, thus seating the valve head 246, unseating the valve head 248, and connecting the opening 226 to the return pipe 254 by means of the piston groove 256.

When the lower valve head 248 is unseated, the pump 210 will merely circulate fluid through the short pipe 252 back to the return pipe 254, and while it is so circulating the fluid, the diaphragm springs 356 and 358 move the diaphragms 340 and 342 back from their deflected positions 341 and 343 to their normal positions 340 and 342.

It is noted that, since the bottom of the piston rod 240 is only slightly larger than the top of the valve head 248, the pressure will be quite high in the servo motor 310 and in the chamber 242 before the piston rod 240 will rise, for the reason that the force tending to raise the piston rod is only the difference between the upward force on the piston rod and the downward force on the valve head.

After the piston 236 has moved to its upper position, a slight pressure will still build up in the chamber 242 due to the resistance to flow in the piping, and this pressure may be accurately controlled by the size of the opening through the pipe 252, and should be such as would exert an upward force on the piston rod 240 which is slightly less than the downward force of the light spring 238, for otherwise the piston 236 would continue indefinitely in the upper position.

As long, however, as the heavy springs 356 and 358 are returning fluid under heavy pressure to and through the opening 226, the piston 236 will remain in the upper position for the reason that, as soon as the piston yields to the light spring 238 and starts to move down, the valve 246 is slightly opened, whereby the slight pressure in the chamber 242 caused by the resistance in the piping is supplemented by the higher pressure of the servomotor entering the chamber 242 through the valve 246. The piston 236 may therefore return to its lower position only when the springs 356 and 358 have put the diaphragm 340 and 342 back to their normal position, i. e., when the fluid which first moved rightwise through the pipe 230 to the servomotor 310 has now returned leftwise through the same pipe 230.

When the diaphragms 340 and 342 thus move

upward, the fluid displaced in expansion chamber 336 can not get out of valve 406 so it moves the servo piston 314 again to the right. The fluid displaced by movement of the servo piston 314 to the right plus the fluid displaced by the upward movement of the diaphragm 342 all passes out through passage 408 and outflow check valve 404 into the supply pipe 230 where it moves to the left, then out through pipe 228, opening 226, piston groove 256 to return pipe 254.

While the servomotor was returning fluid back to the pump intake 212 by way of the piston groove 256, and the pump was circulating fluid from its discharge side back to its suction side by way of the unseated valve head 248 and pipe 252, the pressure dropped in the chamber 242, thereby allowing the spring 238 to reseat the valve head 248, unseat the valve head 246, and return the piston groove 256 to normal, all as shown in Fig. 3 of the drawing, at which point the mechanism starts all over to repeat the cycle.

From the foregoing description it may be seen that, with the valve plug 384 set as shown, the servo piston 314 is moved to the right by flow of fluid in the pipe 230 whether the flow is to the right or to the left in the pipe, whereby the movement of the piston is substantially constant.

In the drawing, Fig. 3, the selector valve 380 is set for moving the servo piston to the right. Movement of the selector valve lever 386 through one quarter turn by the control lever 391 will set the valve for movement of the servo piston to the left.

Other modifications, variants and equivalents are intended to be embraced in the following claims.

I claim:

1. A hydraulic system comprising, in combination, a servomotor having two fluid compartments, fluid actuated means movable by increase of the fluid volume in one compartment and decrease of the fluid volume in the other compartment, power take-off means associated with said fluid actuated means, a chamber in direct communication with each compartment, said chambers each including a displaceable means for varying their volumetric capacity when the amount of fluid is altered therein without a corresponding movement of the fluid actuated means, a single long fluid transfer pipe having one end proximate said compartments and the other end remote therefrom, a fluid transfer means for moving fluid into one of said compartments and withdrawing fluid from the other of said compartments, said fluid transfer means including first, a pump connected to the remote end of said long transfer pipe, second, resilient means for restoring said displaceable means after said displaceable means have been displaced for varying the volumetric capacity of said chambers, and third, a valve mechanism for alternately connecting said proximate end to one compartment when the flow is in one direction and to the other compartment when the flow is in the other direction, 60 and selector means shiftable to reverse the connections of said valve mechanism, whereby, before the shift, said proximate end may be connected to a given compartment for one direction of flow and, after the shift, be connected to the same compartment but for the other direction of flow.

2. In a hydraulic system as defined in claim 1, wherein the fluid moving means comprises a uniform delivery pump and an automatic valve for converting said uniform delivery into an alternat-

ing fluid flow in said pipe, said valve comprising a cylinder, a piston slidable in said cylinder, a compression chamber at one of said cylinder, a rod extending from said piston into said compression chamber, an arm extending laterally from said rod, a valve stem carried at the end of said arm and slidable axially in an opening in said arm, a valve head on each end of said stem, valve seats in opposite walls of said compression chamber spaced apart so that movement of said piston in one direction seats one valve head and movement of the piston in the other direction seats the other valve head, conduit means connecting the one valve seat to said pipe, conduit means connecting the other valve seat to the suction side of said uniform delivery pump, conduit means connecting the compression chamber to the discharge side of said uniform delivery pump, and a port valve in said piston, operative upon movement of said piston by pressure in said compression chamber to connect said long pipe to the suction side of said uniform delivery pump.

3. A hydraulic system comprising, in combination, a closed main cylinder, a piston in said main cylinder dividing the space within said main cylinder into two compartments, a piston rod fast in said piston and slidable in the ends of said main cylinder, an expansion chamber alongside each compartment in direct communication therewith, said expansion chambers each including a diaphragm as one wall thereof and spring means urging said diaphragm outwardly, the diaphragms being deflectible inwardly against the force of the spring means when the volumetric capacity of a chamber is reduced by withdrawing fluid from the chamber without corresponding movement of said piston, valve mechanism operable to two positions for controlling flow into and out of said chambers, said valve mechanism having a common fluid passageway for flow within the body of said valve mechanism and a series of check valves communicating with said common fluid passageway and biased, in one position, for inflow into one chamber and outflow from the other, and biased, in another position, for outflow from the said one chamber and inflow into the said other, a pump cylinder having a piston slidably therein remotely located from the main cylinder, and a long pipe connecting the outlet opening of the pump cylinder to said common fluid passageway of the valve mechanism.

4. A hydraulic system comprising, in combination, a closed cylinder, a relatively long internally bored main piston slidable in said cylinder dividing the space within said cylinder into two compartments, a piston rod extending from said piston and slidable through an opening in the end of said cylinder, two relatively short spaced apart pistons slidable axially in the bore of the main

piston intermediate the middle and ends of said bore, a partitioning member fast in said bore between said short pistons, dividing the space between said short pistons into two smaller spaces, buffer springs in said smaller spaces urging said short pistons away from said partitioning member, expansion spring means between said short pistons and the ends of the main piston urging said short pistons toward each other, the ends of said main piston having end enclosing portions which partly close the ends of the main piston and define contraction chambers between the short pistons and said end enclosing portions, leaving passageways connecting the compartments to the contraction chambers, said end enclosing portions serving as supporting means for the outer ends of said expansion springs, conduit means extending through said partitioning member and through the wall of said main piston and piston rod, to the atmosphere, valve mechanism operable to two positions for controlling flow into and out of said compartments and said contraction chambers, said valve mechanism having a common fluid passageway for flow within the body of said valve mechanism and a series of check valves communicating with said common fluid passageway and biased, in one position, for inflow into one compartment and contraction chamber and outflow from the other compartment and contraction chamber, and biased, in another position, for outflow from the said one compartment and contraction chamber and inflow into the said other compartment and contraction chamber, piping connecting the passageway through said check valves to the two compartments, a pump cylinder having a piston slidably therein remotely located from the main cylinder, and a long pipe connecting the outlet opening of the pump cylinder to the said common fluid passageway of the valve mechanism.
